UNITED STATES PATENT OFFICE.

LESLIE L. HARTWELL, OF WINCHESTER, MASSACHUSETTS.

HEEL-BUILDING MACHINE.

Application filed May 23, 1927. Serial No. 193,492.

My present invention is a novel and improved heel building machine, particularly adapted for assembling and uniting rubber heels and heel bases. In my prior and co-pending application, Serial No. 155,419, filed December 17, 1926, I have described the method of preparing and attaching rubber heels and heel bases, and the present application is directed to a preferred machine for use in carrying out said process.

An important object of the present invention is the provision of means to assemble a rubber heel with its heel base, before said heel and base are delivered to the shoe heeler. In other words, instead of the shoe heeler handling three units, viz., the shoe, heel base, and rubber heel, I reduce the number of units to two, viz., the shoe, and the completely assembled and prepared heel base and rubber heel, firmly united as a single unit.

In carrying out my present invention, I preferably utilize a machine as illustrated in the present application, which machine I believe to be novel, and have therefore claimed broadly herein.

By the use of my novel machine I attach the heel base and the rubber heel, firmly uniting same and preparing both as a unit for simultaneous attachment to the heel portion of the shoe instead of, as formerly, necessitating separate and successive attachments, first of the heel base, and then of the rubber heel. By my invention of thus first assembling the heel base and rubber heel into a single unit, the same can thus be simultaneously attached, the completed heel base and rubber heel being handled as a single article and at a single operation. Furthermore, it is a much easier and simpler proposition to align, assemble and unite the heel base and rubber heel while each are separate, rather than after one of the same is attached to the shoe. Also, in their thus assembled relation, the buffing, trimming or finishing of the heel breast and sides and rear of the heel is greatly simplified, without requiring the time, delay, skill, and machinery necessary to handle the completed shoe and heel in the heel breast scouring action.

Further details of construction, advantages, combinations of parts, and operation, will be hereinafter more fully described and claimed.

Referring to the drawings, illustrating a preferred embodiment of my invention,

Fig. 1 is a front elevation of the machine; Fig. 2 is a rear elevation of the machine; Fig. 3 is a cross sectional view on the line 3—3 of Fig. 1; Fig. 4 is a cross sectional view on the line 4—4 of Fig. 3; Fig. 5 is a cross sectional view on the line 5—5 of Fig. 3; and Fig. 6 is a cross sectional view on the line 6—6 of Fig. 3.

As shown in the drawings, my present novel machine comprises a pair of side frames or supports 1 and 2. A platform or work table 3 is secured thereto and is cut away as shown at 4 to allow the operator close access to the working parts of the machine. A shaft 5 is mounted between the frames 1 and 2, and has thereon a pair of rotating circular frames 6 and 7. Uniting said rotating frames at a plurality of points throughout their outer periphery are a plurality of shafts 8, 8. A driving pulley 9 is mounted on the shaft 5 and an idler pulley 10 is also mounted on said shaft 5, closely adjacent the pulley 9. A belt or other driving instrumentality 11 is illustrated, and adapted to be shifted from pulley 10 to pulley 9 and reverse by a belt shift 12 controlled by a foot treadle 13 pivoted at 14.

In carrying out my novel idea of assembling, clamping, and uniting the rubber heels and their heel bases, as exemplified by the machine of the present application, I utilize a plurality of clamping and uniting devices herein illustrated as six in number, but as the construction, function, and operation of each of these clamping instrumentalities is identical, I will describe herein but a single one of these clamping devices, which description will suffice for all of said clamping devices. While I have herein illustrated six of said clamping devices, it will be appreciated that this is but a preferred embodiment of my invention, and the number of clamping devices is not essential, as I may vary such number without departing from the spirit of the invention.

As shown in detail in Figs. 4 and 5, my novel clamping device comprises a plate or table 15, secured to the cross shafts 8 by screws or bolts 16. A fixed guide 17 is provided on the table 15, having a face 18 against which the rubber heel 19, illustrated in dotted lines in Fig. 4 rests, the heel base 20, illustrated in dotted lines, resting against the guiding portion 21 of said member 17.

An adjustable guide 22 sliding in a guideway 23 and controlled by set screws or the like 24, is also provided. This sliding guide plate 22 has a guiding portion 25 for the rubber heel and a guiding portion 26 for the heel base. The guide 22 is adjustable longitudinally of the plate 15, as will be readily apparent from a glance at Fig. 4. Lateral guides 27 and 28 are also provided, each of these guides having a portion 29 to guide the rubber heel and a portion 30 to guide the heel base. The guides 27 and 28 are fixed to slides 31 and 32 respectively, guideways 33 and 34 being provided therefor, the slides 31 and 32 being controlled by set screws or the like 35, and 36 respectively. I preferably first unite the heel base 20 and rubber heel 19, coating either or both of the contacting surfaces thereof with cement or other adhesive, and then applying same to the clamping and pressure applying device. On being applied on the plate 15 against the guide 17, the guides 22, 27 and 28 are then adjusted to hold the assembled rubber heel and base against lateral or longitudinal slippage. The united heel is applied to the pressure applying device when approximately in the position shown in Fig. 1, with a clamping device illustrated generally as 37 in upright position, a guard 38 and front guard 39 protecting the operator from accident. The assembled units, viz., rubber heel and heel base, are inserted in the guides as above described while the frames 6 and 7, together with their component parts, are rotating, this rotation being caused by the operator depressing the foot treadle 13 and shifting the belt 11 to the driving pulley 9. As viewed in Fig. 1, rotation is in clockwise direction.

To the frame 7, at the rear of each plate 15 is a bracket 40 having a pair of yoked arms 41 between which is pivoted at 43 an arm or lever 42. In the arm 42 is a slot 43. In the slot 43 rides a sleeve 44 mounted on a shaft 45. Also on the shaft 45 are mounted a pair of sleeves 46, 46, having recesses 47 therethrough, and through which recesses extend rods or plungers 48, 48, clearly shown in detail in Figs. 5 and 6. The above described parts are secured on the shaft 45 by nuts 49. Loosely mounted at the front of the arm 42 on a pin 50 is a clamping or pressing plate or plunger 51, which preferably but partially covers the heel base 20. Adjacent the bottom ends of the rods 48 is a bracket 52 and mounted on the bracket 52 is a roller 53, which rides, at certain periods during the rotation of the machine, on a fixed or stationary cam 54. As shown in Fig. 4, rods 48 pass through recesses in the plate 15. The rods 48, and hence the shaft 45 and all parts controlled thereby, are normally held in lowered position, as clearly shown in Fig. 5, by the down-

ward tension of springs 55, one end of each of these springs 55 being secured to pins 56 on brackets 57, which brackets 57 are secured to the bracket 52 and rods 48 by nuts 58. The opposite ends of these springs 55 are attached to similar pins 59 on the clamping instrumentality on the opposite sides of the frames 6 and 7, and in alinement with the clamping device illustrated generally at 37. However, when the assembled heel and base are first inserted in the clamping device, the plunger 51 is in a raised position, as shown in Fig. 3, because of the roller 53 riding on the cam 54, the highest part of the cam 54 being reached when the clamping devices are at the top of the machine. The machine being constantly in rotation, after a united heel and base have been inserted, the roller 53, rotating in anti-clockwise direction, as illustrated in Fig. 2, reaches the point 60 on the cam 54, whereupon the springs 55 exert their tension, pulling the rods 48 downwardly, together with the arm 42 and plunger 51, which plunger 51 thus exerts a strong hammer blow against the assembled heel and base, causing an initial firm uniting of the two members, viz., rubber heel and heel base. The cam 54 is so constructed and arranged, as clearly shown in the drawings, that the full tension of the springs 55 is exerted against the plunger 51, for a sufficient length of time to insure firm, positive and permanent uniting of the rubber heel and base.

At a predetermined point in the periphery 100 of the cam, the roller 53 will again engage said cam, being gradually raised by said cam during continued rotation of the machine. The raising of the roller 53 consequently raises the bracket 52, rods 48, arm 42 and plunger 51, until the roller 53 reaches a point approximately at 61 on the cam 54, at which point the plunger 51 will have been raised from the united heel and base a sufficient distance to permit discharge of said heel and base, which is performed in a manner to be hereinafter described.

As shown in Fig. 5, a bracing and reinforcing member 62 depends from the rear of the plate 15. A reinforcing web 63 extends outwardly and upwardly from the member or portion 62 to plate 15. A sleeve 64, as shown in Fig. 5, is mounted on a cross shaft 8 adjacent the clamping device, this sleeve 64 having thereon a pair of levers 65 and 66. A spring 67 extends from the lever 66 to a circular plate 68 rotatably mounted on the shaft 5, said spring normally holding the levers 65 and 66 downwardly. When, during the rotation of the machine, a clamping device, such for example as illustrated generally at 37, reaches the point generally designated as 61 in Fig. 2, the lever 65 will strike a roll 69 mounted on a small shaft 70, and secured to the frame 2. Contact of the

lever 65 with the roll 69 will move the lever 65 outwardly toward the edge of the machine, also causing the lever 66 to move outwardly toward the edge of the machine against the spring 67, and toward the top of the clamping device. One end of the lever 66 is provided with a recess 71 in which fits a lug 72 which is a part of a slide 73, said slide 73 having a slot 74 adapted to slide over a screw or the like 75. The upper end 76 of the slide 73 enters a slot in the plate 15, and on upward movement of the lever 66, the slide 73 is also raised, thus projecting the then firmly united rubber heel and heel base from the clamping device and into a hopper or the like 77, provided therefor. It will be appreciated that at the time of this discharge of the completed unit the roller 53 of the clamping device under discussion will have contacted with the stationary cam 54, and will have ridden up on said cam a sufficient distance to allow the plunger 51 to be opened or spaced from the united heel and base to permit the discharge of the rubber heel and base from their guides and the plate 15. It will also be apparent from a glance at the drawings that the rods 48 pass through the reinforcing portion 62 as well as through the plate 15. The same arrangement of levers 65 and 66 is provided for each of the clamping instrumentalities.

The springs 55 between each opposite pair of clamping devices are so mounted that they will not interfere with each other throughout their extent across the interior of the machine, the brackets 57 on each clamping device being angled or positioned to insure clearance between the various sets of springs.

It will thus be appreciated that I have devised an extremely efficient, quick acting, and positive machine for the purpose set forth, greatly increasing the speed of shoe manufacture by reason of the reduction in the number of operations heretofore required by the shoe heeler. My present machine is simple in operation, and will be readily understood by those skilled in the art, the operation of same being as follows:

The operator having a plurality of rubber heels and heel bases, either coats one or both of the contacting surfaces of said heels and bases and preliminarily unites the same, or has the thus-united heels and bases delivered to him in this condition, depresses the foot treadle 13, shifting the driving belt 11 to the pulley 9, and setting the machine in operation. Thereupon, as each successive clamping device reaches the top of the machine, accessible to the operator, the operator positions a cemented heel and base in the guides therefor, the plunger 51 being raised by the cam 54; the clamping device passing to the right, as viewed in Fig. 1, then reaches the point 60 on the cam 54,

whereupon the springs 55 exert their tension, and pull the plunger 51 downwardly, jamming it against the heel base, imparting a hammer blow to the united rubber heel and its base. Thereafter, and during the continued rotation of the machine, the springs 55 exert their tension upon the plunger 51, maintaining the heel and base under a constant strong tension, and firmly and positively uniting the same, until reaching the point designated as 61, in Fig. 2, whereupon the clamping device has re-engaged the cam 54, riding thereon until the lever 65 engages the roller 69, whereupon the lever 65 and lever 66 will be moved toward the plate 15, forcing the slide 73 upwardly and through the plate, and discharging the now firmly and permanently united heel and base into any suitable hopper or receptacle, here designated as 77. By the time the clamping device has reached the point 61 on the cam 54 the plunger 51 will have been raised, by action of the rods 48 and component parts, to a height sufficient to permit the discharge of the completely united heel and base.

I believe that my machine as above described is novel, and I have therefore claimed the same herein broadly.

While I have necessarily described my present invention somewhat in detail, it will be appreciated that I am not limited thereto, but may vary the size, shape, and arrangement of parts, within reasonably wide limits without departing from the spirit of the invention.

My invention is further described and defined in the form of claims as follows:

1. In a machine of the kind described, supports, a shaft mounted in said supports, a rotary frame fixed to said shaft, means to impart rotation to said shaft, a stationary cam fixed to one of said supports, a plurality of clamping devices mounted on said rotary frame, each of said clamping devices comprising a plate, adjustable means carried on said plate to receive a heel and heel base, a plunger, and means to operate said plunger to impart impact pressure to said heel and base.

2. In a machine of the kind described, supports, a shaft mounted in said supports, a rotary frame fixed to said shaft, means to impart rotation to said shaft, a stationary cam fixed to one of said supports, a plurality of clamping devices mounted on said rotary frame, each of said clamping devices comprising a plate, adjustable means on said plate to receive a heel and heel base, a spring controlled plunger, and means to operate said plunger to impart impact pressure to said heel and base.

3. In a machine of the kind described, supports, a shaft mounted in said supports, a rotary frame fixed to said shaft, means to

impart rotation to said shaft, a stationary cam fixed to one of said supports, a plurality of clamping devices mounted on said rotary frame, each of said clamping devices comprising a plate, adjustable means on said plate to receive a heel and heel base, a spring controlled plunger, and means to operate said plunger to impart impact pressure to said heel and base and maintain said pressure for a predetermined interval.

4. In a machine of the kind described, supports, a shaft mounted in said supports, a rotary frame fixed to said shaft, means to impart rotation to said shaft, a stationary cam fixed to one of said supports, a plurality of clamping devices mounted on said rotary frame, each of said clamping devices comprising a plate, adjustable means on said plate to receive a heel and heel base, a spring controlled plunger, means to operate said plunger to impart impact pressure to said heel and base and maintain said pressure for a predetermined interval, and means to discharge said united heel and heel base from each of the clamping devices.

5. In a machine of the kind described, supports, a shaft mounted in said supports, a rotary frame fixed to said shaft, means to impart rotation to said shaft, a stationary cam fixed to one of said supports, a plurality of clamping devices mounted on said rotary frame, each of said clamping devices comprising a plate, adjustable means on said plate to receive a heel and heel base, a spring controlled plunger, means to operate said plunger to impart impact pressure to said heel and base and maintain said pressure for a predetermined interval, and means to discharge said united heel and heel base from each of the clamping devices at a predetermined point during rotation of the machine.

6. In a machine of the kind described, supports, a shaft mounted in said supports, a rotary frame fixed to said shaft, means to impart rotation to said shaft, a stationary cam fixed to one of said supports, a plurality of clamping devices mounted on said rotary frame, each of said clamping devices comprising a plate, adjustable means on said plate to receive a heel and heel base, a spring controlled plunger, means on said clamping device cooperating with said cam to permit impact pressure to be imparted to said heel and base and maintained for a predetermined interval, and means to discharge said united heel and heel base from each of the clamping devices.

7. In a machine of the kind described, supports, a shaft mounted in said supports, a rotary frame fixed to said shaft, means to impart rotation to said shaft, a stationary cam fixed to one of said supports, a plurality of clamping devices mounted on said rotary frame, each of said clamping devices comprising a plate, adjustable means on said

plate to receive a heel and heel base, a spring controlled plunger, means on said clamping device cooperating with said cam to permit impact pressure to be imparted to said heel and base and maintained for a predetermined interval, means to discharge said united heel and heel base from each of the clamping devices at a predetermined point during rotation of the machine, said last mentioned means comprising a pair of spring controlled levers, one of said levers operating a slide adapted to penetrate said plate, and means on one of said supports adapted to be engaged by one of said levers to operate said slide.

8. In a machine of the kind described, a shaft, a rotary frame on said shaft, means to impart rotation to said shaft, a plurality of clamping devices on said frame, means carried by each of said clamping devices to receive and hold a heel and heel base, means cooperating with each clamping device to impart impact pressure to the united heel and base, and means to gradually release said pressure.

9. In a machine of the kind described, a shaft, a rotary frame on said shaft, means to impart rotation to said shaft, a plurality of clamping devices on said frame, means carried by each of said clamping devices to receive and hold a heel and heel base, means cooperating with each clamping device to impart impact pressure to the united heel and base, means to gradually release said pressure, and means to eject the united heels and bases from each of said clamping devices.

10. In a machine of the kind described, a shaft, a rotary frame on said shaft, means to impart rotation to said shaft, a plurality of clamping devices on said frame, each of said clamping devices being positioned directly opposite another clamping device, means carried by each of said clamping devices to receive and hold a heel and heel base, means cooperating with each clamping device to impart impact pressure to the united heel and base, means to gradually release said pressure, and means to eject the united heels and bases from each of said clamping devices.

11. In a machine of the kind described, a shaft, a rotary frame on said shaft, means to impart rotation to said shaft, a plurality of clamping devices on said frame, each of said clamping devices being positioned directly opposite another clamping device, means carried by each of said clamping devices to receive and hold a heel and heel base, means cooperating with each clamping device to impart impact pressure to the united heel and base, said last named means being controlled by a spring extending between opposite pairs of said clamping devices, means to gradually release said pressure,

and means to eject the united heels and bases from each of said clamping devices.

12. In a machine of the kind described, a shaft, a rotary frame on said shaft, means to impart rotation to said shaft, a plurality of clamping devices on said frame, each of said clamping devices being positioned directly opposite another clamping device, means carried by each of said clamping devices to receive and hold a heel and heel base, means cooperating with each clamping device to impart impact pressure to the united heel and base, said last named means being controlled by springs extending between opposite pairs of said clamping devices, means to gradually release said pressure, and means to eject the united heels and bases from each of said clamping devices.

13. In a machine of the kind described, a shaft, a rotary frame on said shaft, means to impart rotation to said shaft, a plurality of clamping devices on said frame, each of said clamping devices being positioned directly opposite another clamping device, means carried by each of said clamping devices to receive and hold a heel and heel base, means cooperating with each clamping device to impart impact pressure to the united heel and base, said last named means being controlled by springs extending between opposite pairs of said clamping devices, means to gradually release said pressure, and means to eject the united heels and bases from each of said clamping devices, each pair of springs uniting a pair of clamping devices being disaligned from the other pairs of springs.

14. In a machine of the kind described, supports, a shaft mounted in said supports, a rotary frame fixed to said shaft, means to impart rotation to said shaft, a stationary cam fixed to one of said supports, a plurality of clamping devices mounted on said rotary frame, each of said clamping devices comprising a plate, adjustable means on said plate to receive a heel and heel base, a spring controlled plunger, a roller carried by each of said clamping devices adapted to engage said cam and be released from said cam at the highest point thereof to permit impact pressure to be imparted to each of said heels and bases and maintained for a predetermined interval, means to discharge said united heel and heel base from each of the clamping devices at a predetermined point during rotation of the machine, said last mentioned means comprising a pair of spring controlled levers, one of said levers operating a slide adapted to penetrate said plate, and means on one of said supports adapted to be engaged by one of said levers to operate said slide.

15. In a machine of the kind described, a pair of supports, a shaft mounted in said

supports, a pair of rotary frames fixed to said shaft, a plurality of shafts connecting said rotary frames at their outer periphery, means to impart rotation to said first shaft, a stationary cam fixed to one of the said supports, a plurality of clamping devices mounted on the shafts between said rotary frames, each of said clamping devices comprising a plate, fixed and adjustable means on said plate to receive a heel and heel base, a spring controlled plunger, and means on said clamp- 75 ing device cooperating with said cam to permit said plunger to impart impact pressure to said heel and base and maintain said pressure for a predetermined interval.

16. In a machine of the kind described, a pair of supports, a shaft mounted in said supports, a pair of rotary frames fixed to said shaft, a plurality of shafts connecting said rotary frames at their outer periphery, means to impart rotation to said first shaft, a stationary cam fixed to one of the said supports, a plurality of clamping devices mounted on the shafts between said rotary frames, each of said clamping devices comprising a plate, fixed and adjustable means on said plate to receive a heel and heel base, a spring controlled plunger, means on said clamping device cooperating with said cam to permit said plunger to impart impact pressure to said heel and base and maintain said pressure for a predetermined interval, and means to discharge said united heel and heel base from each of the clamping devices at a predetermined point during rotation of the machine.

17. In a machine of the kind described, a pair of supports, a shaft mounted in said supports, a pair of rotary frames fixed to said shaft, a plurality of shafts connecting said rotary frames at their outer periphery, means to impart rotation to said first shaft, a stationary cam fixed to one of the said supports, a plurality of clamping devices mounted on the shafts between said rotary frames, each of said clamping devices comprising a plate, fixed and adjustable means on said plate to receive a heel and heel base, a spring controlled plunger, means on said clamping device cooperating with said cam to permit said plunger to impart impact pressure to said heel and base and maintain said pressure for a predetermined interval, and means to discharge said united heel and heel base from each of the clamping devices at a predetermined point during rotation of the machine, said cam and cam operated means holding the plunger in raised position for a predetermined interval to permit refilling of said clamping device.

In testimony whereof, I have signed my name to this specification.

LESLIE L. HARTWELL.
